UNITED STATES PATENT OFFICE.

JAMES H. COLLINS, OF HARRISBURG, PENNSYLVANIA.

TOY.

1,129,551.

Specification of Letters Patent. Patented Feb. 23, 1915.

Application filed March 21, 1914. Serial No. 826,160.

To all whom it may concern:

Be it known that I, JAMES H. COLLINS, of the city of Harrisburg, county of Dauphin, State of Pennsylvania, have invented 5 certain new and useful Improvements in Toys, and of which the following is a full and exact description.

The object of the invention is to provide a novel toy for both boys and girls, which 10 can be manufactured at an extremely low cost, and which will not easily become broken or disarranged.

Another object is to provide a toy which, 15 like a pistol, is held in the hand and operated by a single finger; one which will not make an objectionable noise or in any way endanger the life of the user; one which will not fly, as aerial toys, into inaccessible places, or lead the user into dangerous 20 places; and one which will be so unique and unusual in its appearance and operation, as to attract and hold the attention and interest of children and adults of both the sexes.

25 Still another object is to provide in such a toy, a novel form of self-cocking mechanism, and an improved arrangement and operation of the parts of the trigger release or escapement mechanism. And another object is to provide in a modification of such 30 a toy a simple mechanism that will efficiently make the animal or other automaton rear or kick upon its fore feet and then jump backward, or vice versa; or to kick 35 its hind legs outwardly as it rises upon its fore feet.

Further objects and more specific details of the operation of the device are herein-after fully brought out in the following description, when read in conjunction with the accompanying drawing, in which—

Figure 1 is a side elevation of the preferred embodiment of the invention, with the operating mechanism exposed; Fig. 2 is 45 a fragmentary detail view of the same in its other extreme position; Fig. 3 is a perspective view of one of the body sections; Fig. 4 is a side elevation of a modified form of the device, showing the 50 operating mechanism exposed to view; and Fig. 5 is a similar view of a third embodiment of the invention.

Referring to the drawings, the preferred embodiment of the invention comprises a 55 body member or frame of metal, composed

of two similar sections 10 and 11, respectively, held together by suitable means such as screws 12, and having the appearance of a pistol, revolver, or in fact any desired type of fire-arm. Each of these sections is 60 recessed at 15, said recesses coöoperating to form an inclosure for the operating mechanism of the device and opening outwardly at 16 and 17. When made of wood or composition the body member is made of one 65 piece and the recess 15, is mortised therein. In said inclosure is a trigger 18, pivotally carried by a transversely extending pin 19, extending between and secured in the two sections 10 and 11, and comprising a finger-engaging projection 20, spring-engaging recess 21, and locking lug 22, said projection extending downwardly through the inclosure outlet 17, and being provided with a shoulder 23, to limit its movement in one direction. Also located within said inclosure 75 is a rocking member 25, pivotally mounted upon a transversely extending pin 26, secured at its ends in the sections 10 and 11, said member being recessed at 27 for cooperation with the trigger lug 22, and being provided with a stop projection 28, having a spring-engaging recess 29, and adapted to coöperate with the angle portion 30 of the said trigger, to limit the movement 85 of said member in one direction.

The rocking member 25 has integrally secured thereto any desired automaton, or animal-representing figure 36, such for instance as the mule, shown in the drawing, 90 and the various parts of the device are normally as represented in Fig. 1, with the rear hoof 33 resting upon the sections 10 and 11 and the spring 34 extending between the trigger lug 22 and the projection 28, and 95 engaging said elements in the recesses 21 and 29, respectively. In this position the spring is curved slightly around the under surface 35 of the rocking member 25, which fact creates a pull around the pin 26, instead of substantially in alinement with the same, said arrangement also tending to maintain one end of the spring on the lug 22. Upon releasing the trigger by a rearward pressure upon the projection 20, the spring pulls the projection 28 suddenly forward, thus making the automaton 26 kick upwardly in the air. In this last position, illustrated by Fig. 2, the movement of the automaton 100 is shown to have been stopped by the en- 105

gagement of the projection 28 with the portion 30 of the trigger, while the spring assumes a curved position about said portion, the trigger being restrained from further movement than that shown, by the co-operation of the shoulder 23 with the under side of the sections 10 and 11. Thus, in this position, with the projection 28 in a downward position, the spring is prevented from disengagement with the recess 25 by contact with said trigger.

In the modification shown in Fig. 4, the pin 26 passes through one end 30 of an elongated, curved slot 35 in the rocking member 25 and, from the position shown in full lines, said member upon the release by the trigger, swings about said pin until the projection 37 of the slot wall passes out of alignment with said pin, after which the member takes a curved path forwardly until the pin reaches the opposite end of said slot.

In its preferred form the device is self-cocking, the weight of the movable object overcoming the spring as the device after being firmly gripped, is dropped sharply downwardly and suddenly arrested, lug 22 automatically engaging within the recess 25, and thus re-setting the trigger for a repetition of the operation. In the modified form it is necessary to recock or reset the device by manually operating the automaton against the tension of the spring.

In the modification shown in Fig. 5, the mule or other automaton 26' is pivotally mounted as shown in Fig. 1 upon a suitable pin 26 and actuated by a spring or other resilient member 34 upon the operation of the trigger 20. However, in this case, the hind legs 40 are pivoted at 41 to the body 26' and provided with a short extension 42 to which a link 43 is pivoted at 44, the other end of said link being pivotally attached in any suitable manner and position as at 45 to the frame member or members 10 and 11. In this form of the device the rear portion of the animal rises suddenly upon releasing the trigger, and the extension 42 being held by the link 43 against similar movement, the legs 40 as suddenly undergo a change of position characteristic of the act of kicking. Upon resetting the device, the legs reverse their former action and again assume the upright or standing position.

Having described my invention, what I claim and desire to protect by Letters Patent of the United States is:

1. The combination of a frame, an automaton carried thereby, means to maintain said automaton in a given position, and resilient means extending between said automaton and said first means to move said automaton upon its release by said first-mentioned means.

2. A toy comprising a frame, an automaton pivotally carried thereby and pro-

vided with a lug, a lever pivotally carried by said frame and operative to engage the lug of said automaton and a resilient member extending between said automaton and said lever to cause a positive engagement of said lug and lever when in locked position.

3. A toy comprising a frame, an automaton pivotally carried thereby and provided with a lug, a lever pivotally carried by said frame and operative to engage the lug of said automaton, and a resilient member extending between said automaton and said lever to cause the co-operation of said lever and the lug of said automaton.

4. A toy comprising a frame, an automaton pivotally carried thereby, a lever pivotally carried by said frame, a projection extending from said lever and operative to engage said automaton, and a resilient member connecting said automaton and said lever, to cause their positive co-operation when in locked position.

5. The combination of an automaton, a relatively stationary frame, a manually operative lever pivoted to said frame, and adapted to co-operate with said automaton to yieldingly maintain the latter in a given position, and a resilient member extending between said lever and said automaton and partially encircling said lever when in one extreme position and partially encircling said automaton when in the opposite extreme position.

6. The combination of an automaton, a relatively stationary frame, a manually operative lever pivoted to said frame, and adapted to co-operate with said automaton to yieldingly maintain the latter in a given position, and a resilient member extending between said lever and said automaton and partially encircling said lever when in one extreme position and partially encircling said automaton when in the other extreme position, said lever operating as a stop for said automaton in one direction.

7. The combination of an automaton having a projection, a relatively stationary frame, a manually operative lever pivotally carried by said frame, and adapted to co-operate with said automaton to maintain the latter in a given position, and a spring extending between said lever and said projection, and partially encircling said lever when in one extreme position, and partially encircling said automaton when in the other extreme position, said projection co-operating with said lever to stop the movement of said automaton in one direction.

8. A toy comprising a frame, an automaton provided with an irregular slot, a relatively stationary pin carried by said frame portion and extending through said slot, a trigger co-operating with said automaton to maintain the latter normally in a given position, and a resilient member oper-

ative to actuate said automaton upon said pin, as said automaton is released by said trigger.

9. A toy comprising a frame, an automaton provided with an irregular slot, a pivot pin carried by said frame portion and extending through said slot, a trigger co-operating with said automaton to maintain the latter normally in a given position with said pin at one end of said slot, and a resilient member operative to actuate said automaton upon said pin, as said automaton is released by said trigger, said pin moving longitudinally with respect to the slot after which said automaton swings upon said pin as a pivot.

10. The combination of a frame, an automaton and a lever secured thereto and provided with inter-engaging lugs, and a resilient member extending between said automaton and said lever and operative to cause a positive engagement between said lugs.

11. The combination of a frame, an automaton and a lever pivotally secured there-

to, and a resilient member secured to said automaton and said lever, said automaton and lever being provided with inter-engaging lugs, so situated with respect to the points of pivotal support that when in locked position any separation of the lugs must take place against the tension of said resilient member.

12. The combination of a frame, an automaton provided with a lug, a second and manually operated member provided with a lug, and a resilient member supported by said automaton and said member independently of said frame and causing the positive co-operation of said lugs, and so situated that when said lugs are in locked position, any separation thereof must take place against the tension of said resilient member.

In witness whereof, I have hereunto set my hand this 19th day of March A. D., 1914.

JAMES H. COLLINS.
